UNITED STATES PATENT OFFICE.

ARTHUR E. CHAPPELL, OF CHICAGO, ILLINOIS.

SURFACING-MACHINE.

1,389,125.

Specification of Letters Patent. Patented Aug. 30, 1921.

Application filed October 3, 1918. Serial No. 256,672.

To all whom it may concern:

Be it known that I, ARTHUR E. CHAPPELL, a citizen of the United States, residing at Chicago, in the county of Cook and State 5 of Illinois, have invented certain new and useful Improvements in Surfacing-Machines, of which the following is a specification.

This invention relates to floor dressing or 10 surfacing machines which are employed for the purpose of producing a smooth surface on floors, bowling alleys, etc., and aims to provide a manually operated power driven machine of this character which will be 15 simple and compact in construction, and at the same time strong and durable, and which will readily permit of the various adjustments of the surfacing tool which are required in order to obtain the most satisfactory results.

In these machines it is essential that the surfacing tool, which is usually an emery covered cylinder or drum, be so mounted that it may be accurately adjusted to perfect 25 parallelism with the floor. This has usually been done by making the bearings of the tool adjustable on and relatively to the frame of the machine. In my present invention these bearings are rigid with the 30 machine frame, and one object of the present invention is to provide a simple and improved means for adjusting the sides of the machine frame vertically relatively to its supporting axle.

In machines of this kind it has also heretofore been customary to mount the shaft of the surfacing tool in a bearing located at a greater or less distance from one end of the tool, and this produces an undesirable lateral 40 vibration or shake in the shaft which is both annoying to the operator and impairs the efficiency of the tool and the accuracy of its work. Another object of the present invention, therefore, is to eliminate these 45 faults which I accomplish by providing an elongated shaft support having spaced bearings, and a surfacing drum having an inset head at the end next to the shaft support so that that end of the working surface of the 50 drum considerably overhangs the adjacent bearing.

Another object of my invention is to provide a machine with a reversible surfacing cylinder and a removable shaft, the shaft 55 being removable from the bearings and the

cylinder being detachable from the shaft so that the cylinder may be reversed in position or another cylinder may be substituted without changing the shaft, or another shaft may be substituted without changing the 60 cylinder.

A further object of the invention is to provide an improved means for locking the drum shaft in its bearings at the end of the shaft support opposite that at which the 65 drum is applied, and for keying the drum on the shaft, as well as taking up wear and preventing end play of the shaft or the drum on the shaft; at the same time making it easy to transfer the drum and shaft to 70 the opposite side of the machine frame, when required, for the purpose of occasionally reaching portions of the floor not accessible to the drum in its regular or normal position.

Still another object of the invention is to provide an improved dampener for a handle-pole or shank which carries the handle-bar, designed to cushion and absorb the vibrations of the frame created by the surfacing tool and prevent their transmission to the handle. This is especially useful and desirable in a machine, such as that of the present invention wherein the driving shaft of the surfacing tool is journaled in the bearings that are rigid with the machine frame.

These and other objects and advantages of the invention will be better appreciated as the same is more fully understood from the following description when considered 90 in connection with the accompanying drawings, wherein I have shown one practical and workable embodiment of the invention, and in which,—

Figure 1 is a side elevation of my improved surfacing machine;

Fig. 2 is a substantially vertical section taken on the line 2—2 of Fig. 1, this figure also showing in dotted lines the reversed position of the surfacing drum and its shaft 100 relatively to the machine frame;

Fig. 3 is a substantially vertical section taken on the line 3—3 of Fig. 1;

Fig. 4 is an enlarged fragmentary detail view illustrating means for adjusting one 105 end of the frame supporting shaft in one side of the frame; and

Fig. 5 is an enlarged fragmentary view in vertical section, illustrating the means for dampening or cushioning the stem or 110

pole of the handle against vibrations of the frame.

Referring to the drawings, the frame of the machine comprises a top plate 6, substantially vertical parallel side plates 7 and 8, the former of which extends some distance in advance of the latter, and a narrow front wall 9, this latter terminating at its lower end in an elongated hub 10 which supports the bearings of the shaft of the surfacing tool. This frame is supported substantially midway of its ends on a two-wheel truck comprising an axle 11 and a pair of wheels 12 journaled on opposite ends of said axle. As shown in Figs. 3 and 4, the axle 11 is mounted at one end in an opening 13 formed in the side wall 7 near its lower end; and at its other end said axle engages a vertical notch 14 (Fig. 4) formed in the lower edge of the side wall 8. The portion of the axle lying within said notch has a transverse threaded opening 15 through which passes a screw 16 the upper end of which abuts against the top or closed end of the notch 14. By turning the screw 16, the side 8 of the frame is raised or lowered relatively to the opposite side 7; and a lock nut 17 is preferably provided on the screw 16 to check accidental turning of the screw in the shaft. Extending through the hub 10 and supported by anti-friction bearings 18 in each end of the latter is a shaft 19, on which is mounted a surfacing drum or tool 20. Preferably the outer end of the shaft 19 is provided with a head or cap 21 carrying a pin or key 22 which enters a hole in the outer head of the drum to lock the latter non-rotatably on the shaft. The opposite head of the drum has a central inset portion 23 that overhangs the adjacent end of the shaft supporting hub 10, thus bringing the anti-friction bearing 18 at that end of the shaft support well within and between the ends of the drum. By thus causing the drum to overhang the adjacent bearing of its shaft, the lateral vibration or shake of the shaft and drum is greatly reduced as compared with the usual mounting wherein the drum lies at a greater or less distance beyond the bearing.

The opposite end of the shaft 19 projects beyond the other bearing and carries thereon a sprocket wheel 24 detachably locked to the shaft by a set screw 20' or other preferred means. Beyond the hub of the sprocket wheel there is fitted on the projecting end of the shaft a sleeve 25, the inner end of which abuts against the end of the sprocket hub while its outer end projects slightly beyond the end of the shaft, as shown in Fig. 2. The outer end of sleeve 25 is covered by a disk 26 through which passes a screw 27 engaging a tapped hole in the end of the shaft. By tightening up

the screw 27, the shaft 19 is locked securely in its bearings and also adjusted to take up any end play of the shaft or of the drum on the shaft resulting from wear. To prevent accidental disengagement of the screw 27, the disk 26 is locked to the shaft so as to rotate with the latter by a locking pin 28 passing through said disk and into the end of the shaft. This construction also locks the sprocket wheel 24 against accidental displacement longitudinally of the shaft 19.

In case it is desired to transfer the surfacing drum to the opposite side of the machine, it is necessary only to back out the screw 27, withdraw the shaft 19 endwise from its bearings and from the drum 20, transfer the drum 20 without inverting it, to the opposite side of the machine frames, insert the shaft 19, turned end for end, and secure its projecting end by the means already described. For locking the drum on the shaft in this changed position, the inset end 23 is provided with a hole 29 that is engaged by the locking pin 22, as illustrated in the dotted line position of the parts shown in Fig. 2.

Journaled in and between the side walls 7 and 8 above the shaft 11 is a fan shaft 30 (Fig. 3) equipped at one end with a sprocket wheel 31. Keyed on this shaft is a centrifugal fan 32 housed within a sheet metal casing 33, this latter having in one side wall thereof a suction opening or inlet 34 that communicates with a conical induction passage formed by a sheet metal casing 35 extending between the inner side of the fan casing and the opposite side of the machine frame and open on the side thereof lying next to the surfacing tool. The fan casing 33 is provided with an eduction spout or nozzle 36 to which may be attached a bag (not shown) for catching the dust.

Rigidly mounted on the top plate 6 of the frame is an electric motor conventionally illustrated at 37, the armature shaft of which carries a sprocket wheel 38. A sprocket chain 39 trained around the sprocket wheels 38, 31 and 24 serves to drive both the surfacing tool and the fan at proper relative speeds.

The pole or shaft carrying the handle by which the machine is controlled and directed over the floor surface, comprises, as herein shown, a lower section 40 having a forked lower end that is secured on the truck shaft 11, and an upper section 42 secured to the lower section by screws 43, and carrying at its upper end the transverse handle 44. On the section 42 of the pole is mounted a controller 45 for the electric motor, which controller may be of any desired or approved make, and has nothing to do with the present invention.

Where, as in the present case, the bearings

of the drum shaft are rigid with the machine frame, the vibrations of the drum and its shaft are, of course, transmitted to the frame and from the latter to the pole and handle. My invention includes a simple device by which the manual propulsion and guidance of the machine are rendered easier on the operator by cushioning or absorbing the machine frame vibration. This device is shown principally in the detailed view Fig. 5 wherein 46 designates a bracket plate secured to and beneath the rear edge of the top frame plate 6, and 47 designates a metal strap or yoke secured to and opposite the plate 46. Between the members 46 and 47 are cushions 48 of felt or like yieldable material, between which passes the pole piece 40. A clamping screw 49 threaded through the yoke 47 engages a thin backer or shim 50 by which the cushions 48 are tightly compressed on the shank or pole 40. By this construction the pole and handle are secured to the machine frame with sufficient rigidity for propulsion and guidance purposes, and at the same time the pole and handle are effectively cushioned against the vibrations, which are practically all absorbed by the cushions 48.

Depending from the underside of the pole member 40 is a leg or standard 51 (Fig. 1) by which the machine may be supported with the surfacing tool off the floor when not at work in an obvious manner. To the forward edge of the top plate 6 of the frame 35 is attached, by thumb screws 52, a guard or cover 53 that extends down over the forward or advance side of the surfacing cylinder. The purpose of this guard is to prevent the dust and other material loosened by the surfacing tool from being thrown forwardly of the machine, and to assist the action of the fan in drawing the dust through the machine into the dust receptacle or catcher. A handle 54 is provided at 45 the front of the machine by which it may be lifted when necessary.

It is believed that the construction and operation of my invention will be readily understood from the foregoing without further description, and it should be obvious that I have provided a floor dressing machine which is extremely simple and compact in construction, in which the surfacing tool may be readily adjusted to perfect 55 parallelism with the floor and may readily be transferred to the opposite side of the machine when necessary or desirable, in which the vibrations of the machine are effectually cushioned and prevented from reaching the 60 operating handle to any serious extent, and in which all of the parts can be economically made and readily assembled.

The invention, however, is not limited to the structural details shown and described 65 but it is capable of embodiment in struc-

tures differing widely in mechanical detail from those employed herein for purposes of illustration merely.

I claim:

1. In a surfacing machine, the combination 70 of a frame having substantially vertical side members, one of said members being formed with a shaft-receiving opening near its lower edge and the other with a shaft-receiving notch in its lower edge, a shaft mounted in 75 said opening and notch, an adjusting screw threaded through said shaft and abutting against the top of said notch, wheels on the ends of said axle, and a surfacing tool carried by said frame. 80

2. In a surfacing machine, the combination 85 of a frame provided with an elongated bearing, a shaft journaled therein, a surfacing cylinder having spaced end walls adapted to receive said shaft, one of said end walls being spaced inwardly from the end of the cylinder to dispose said end around said bearing, means for locking said cylinder against rotation relatively to said shaft, means for rotating said shaft, and means for retaining said 90 shaft in its bearing.

3. In a surfacing machine, the combination 95 of a frame having a narrow projecting portion provided with an elongated bearing extending laterally beyond said portion, a shaft 100 reversibly journaled in said bearing and provided at one end with a locking pin, a surfacing cylinder mounted upon one end of said shaft and locked thereto by said pin, said cylinder overlapping and surrounding the extended end of said bearing, means at the other end of said shaft for preventing displacement of the shaft from its bearing and for regulating the end play of said shaft in its bearing and a sprocket wheel mounted 105 on said shaft.

4. In a surfacing machine, the combination 110 of a frame provided with an elongated bearing, a shaft, a surfacing cylinder reversibly mounted thereon and adapted in one position to overlap one end of said bearing, means for locking said shaft in the bearing, and detachable means for driving said shaft, said driving means being removable to permit endwise reversal of the shaft so that said cylinder 115 may be disposed at will upon either side of the bearing and reversed endwise upon the shaft.

5. In a surfacing machine, the combination 120 of a frame, a shaft-support carried by said frame, a shaft journaled in and projecting at its ends beyond the ends of said shaft-support and carrying a pin key, a surfacing drum formed with a hole and mounted on one projecting end of said shaft, and means on the 125 other projecting end of said shaft for drawing said shaft endwise to key it to said drum and for locking it against endwise displacement.

6. In a surfacing machine, the combination 130

of a frame, a shaft-support carried by said frame, a shaft journaled in and projecting at its ends beyond the ends of said shaft-support and carrying a pin, a surfacing drum formed 5 with a hole for said pin and mounted on one projecting end of said shaft, a driving member fast on the other projecting end of said shaft, a sleeve mounted on said last-named shaft-end, said sleeve abutting at its inner 10 end against the hub of said driving member and at its outer end extending beyond said last-named shaft-end, a disk bearing against the outer end of said sleeve, and an adjusting and locking screw passing through said disk 15 and tapped into said last-named shaft-end.

7. In a surfacing machine, the combination of a frame having a narrow forwardly extending portion terminating in a horizontal bearing projecting laterally in opposite di-

rections beyond said portion, a surfacing 20 cylinder having a diametral wall at one end and an inwardly recessed wall at the opposite end adapted to receive and surround the projecting end of said bearing, a shaft journaled in said bearing and projecting outwardly 25 therefrom at each end, means carried by one end of said shaft for detachably engaging with either end wall of said cylinder to lock said cylinder against rotation on the shaft, a driving wheel mounted on the other projecting end of said shaft, and means carried by 30 said end of the shaft for locking said wheel against displacement and for taking up end play in the shaft, said shaft being reversible in said bearing and said cylinder being reversible on said shaft. 35

ARTHUR E. CHAPPELL.
